UNITED STATES PATENT OFFICE.

RAY TRAUTMAN, OF MINNEAPOLIS, MINNESOTA.

ARTIFICIAL LIMB.

1,319,813.

Specification of Letters Patent.

Patented Oct. 28, 1919.

Application filed April 23, 1918. Serial No. 230,218.

To all whom it may concern:

Be it known that I, RAY TRAUTMAN, a citizen of the United States, residing at Minneapolis, in the county of Hennepin and 5 State of Minnesota, have invented certain new and useful Improvements in Artificial Limbs, of which the following is a specification.

My invention relates to artificial limbs 10 and has for its object the manufacture of artificial limbs in which hollow shell members are formed of fiber. The fiber which I prefer to use is an artificial product formed by chemically-treated cotton and linen cloth 15 or other fibrous material. It is hard, tough and durable and in addition to these properties possesses great lightness, which makes it very desirable for artificial limbs. When kept in water for a considerable period of 20 time the sheet fiber becomes sufficiently softened to be readily molded into the proper shape. So far as I am aware the fiber which has heretofore been used for this purpose has either been bleached or has 25 been colored by the addition of coloring matter. If the fiber is not bleached or colored it is of a natural gray color and is much stronger than that which has been subjected to the action of a bleaching agent 30 or which has been mixed with coloring matter. I have discovered that by sufficiently softening the natural gray fiber it can be shaped to form artificial limbs which are much stronger and more durable than those 35 which are formed from the fiber previously used. After this natural gray fiber in sheet form has been sufficiently softened I mold 40 it into the shape desired for the articles, or limbs, bringing the longitudinal edges of the shell together to form a butt-joint. This joint is held together and strengthened by an outer strip preferably of natural gray fiber and preferably also by an inner metal strip.

45 The fiber which I employ is designated more particularly as mechanical natural gray fiber and so far as I am aware has never before been used for shell members of artificial limbs nor for analogous articles. 50 Shell members made of this material are much stronger and much more durable than when made of the fiber which was in use before the time of my invention.

55 The full objects and advantages of my invention will be understood by referring

to the detailed description and are particularly pointed out in the claims.

Referring to the accompanying drawings, which illustrate my invention embodied in an artificial limb to be used for amputations 60 both above and below the knee,

Figure 1 is a side view partly in section showing a thigh, shank and foot members. Fig. 2 is a rear view thereof. Fig. 3 is a view in cross-section on the line 3—3 of 65 Fig. 2. Fig. 4 is a side view with a portion of the shell broken away to show the attachment of the foot member.

The drawings illustrate an artificial limb comprising a thigh member 10, a shank 70 member 12 and a foot member 14. The members 10 and 12 are hollow shells preferably formed of mechanical natural gray fiber. The member 12 is molded in the proper shape and has the two longitudinal 75 edges of the shell brought together at the rear to form a butt-joint, as best shown in Fig. 3. The butt-joint is held together and the member is strengthened by an outer strip 16 preferably of mechanical natural gray 80 fiber and an inner metal strip 18 which are secured together by silver nails 20 passing through the shell and the two strips at both sides of the abutting edges of the shell and riveted in place. The ankle bolt 22 passes 85 through the shank member near its ankle portion in the customary manner, and in order to provide additional strength at this place a short metal strip 24 through which the bolt passes is secured over the metal 90 strip 18.

The thigh member 10 which I illustrate is also preferably formed of mechanical natural gray fiber molded into proper shape and having the two longitudinal edges of the 95 sheet brought together at the rear to form a butt-joint. This joint is held together by an outer strip 26 preferably of mechanical natural gray fiber and an inner metal strip 28 secured together by silver nails 30 passing through the shell and the two strips at both sides of the abutting edges of the shell and riveted in place.

The knee joint is formed by a bolt 32 passing pivotally through the stub end 34 105 of the thigh member, to which bolt is secured the rear connecting member 36 which is secured at its other end to the shank portion, while a notch 38 is provided in the stub end 34 to permit movement of the 110

member 36. Also secured to each end of the bolt 32 is a metal strip 42 which extends down inside the shank member and is riveted thereto. Rotatably mounted in a 5 recess in the stub end 34 is a fiber roller 44 over which passes a strong, heavy cord 46, the lower end of which is secured to the rear portion of the shank member. The upper end of this cord is attached to a heavy elastic strap 48 which in turn is attached at 10 a suitable place such as to the suspender 50 by the adjusting buckles 52. The suspender passes over the shoulder in the usual manner and its other end has a loop 54 through 15 which passes a heavy cord 56. This cord passes down each side of the thigh member through a guide 58 carried by a strap 60 secured to the thigh member, then passing under a roller 62 which is secured to the 20 thigh member through a loop 64 in the strap 60, and finally through a loop 66 at the front end of the suspender, the meeting ends of the cord coming from adjacent sides being secured together.

25 As best shown in Fig. 4, the foot member is shown secured to the shank member so as to have a rocking movement relatively thereto. A metal strip 68 is secured inside of the shank member at each side thereof 30 by rivets 70, and the lower ends of the two strips are secured to a rod 72 which is rotatably mounted in a trunnion 74 secured to the foot member by a bolt 75 passing vertically therethrough. An elastic member 35 76 and a strong heel cord member 78 are attached to the foot member at points located respectively in front of and back of the strips 68, and the upper ends of these members are attached to the ankle bolt 22. 40 On account of this construction, the foot member is normally held positioned as shown in Fig. 4, but is permitted to have a rocking movement about the rod 72 as a pivot. When the wearer of the artificial 45 limb is walking, the heel portion naturally comes first into contact with the ground, and the elastic member 76 yields and allows the toe portion to swing down with an easy movement, thereby eliminating jarring. 50 When the weight of the person comes upon 55 the toe, the heel cord 78 exerts a strong pull on the ankle bolt 22. On account of this bolt passing through the reinforcing strips near the place of attachment of the heel cord to the bolt, liability of the bolt tearing loose from the fiber shell is avoided. A slip socket 80, shown in dotted lines in Fig. 4, receives the lower end of the portion of the leg which is left when amputations are 60 made below the knee. The slip socket extends down into the shell 12, the top of which is shaped to form curves extending downwardly from the sides toward the front and back, the back curve extending downwardly somewhat farther than the front 65

curve. Secured to the top of the slip socket 80 is a collar 82, the lower edge of which is shaped to correspond with the curved top of the shank member 12. On account of this interfitting of the shell of the shank member 70 and the collar of the slip socket, any twisting or turning movement of the thigh of the person will be communicated to the shank member and the foot member. Secured to each side of the shank member 12 is a forked 75 connecting member, the two branches 84 of which are riveted to said shank member. To the conjoint end 85 of the forked member is pivotally connected at 86, a connecting member 88 which extends upwardly and is 80 secured to a leather lacer 90 which is adapted to be secured around the thigh of the wearer by a lacing 92. The collar 82 of the slip socket is connected to the lacer 90 by a member on each side having an elastic portion 85 94. A construction is thus provided which serves to connect the artificial shank member with the thigh of the person, while at the same time permitting free and easy movement of the knee. The forks 84 furnish a 90 strong connection with the shank member whereby danger of breaking is avoided.

In use, the stump of the leg below the knee is placed in the slip socket and the lacer is secured around the thigh while the slip socket is attached to the lacer at both sides by means of the elastic members 94. When the foot member is off the ground, the elastic members raise the slip socket 95 slightly from the upper end of the shank 100 member, while in walking when the foot member contacts with the ground, the slip socket moves down until the collar thereon comes into contact with the upper edge of the shank member. This stretches the elastic 105 members and results in a cushioning effect which eliminates jarring. The slip socket is at all times held closely upon the stump portion of the leg and chafing thereof is prevented. 110

The operation and advantages of my invention will be obvious from the foregoing description. Artificial limbs made from mechanical natural gray fiber are extremely light and at the same time strong and durable. The construction of the artificial limb as an entirety is such as to make it extremely light and strong and at the same time to permit free and easy movement of the shank and foot members relatively to the thigh 115 and of the foot member relatively to the shank member. Shocks are absorbed and the comfort of the wearer is insured not only on account of the avoidance of jarring of the person, but also on account of the 120 prevention of chafing. 125

I claim:

1. An artificial limb comprising a hollow shell formed from a sheet of fiber, the longitudinal edges of which are brought 130

together to form a butt-joint, a strip of fiber secured on the outside of the shell to both of the abutting edges of the joint, and a metal strip secured on the inside of the shell 5 to both of the abutting edges of the joint.

2. An artificial limb comprising a shank member and a thigh member pivoted together to form a knee joint, a roller rotatably mounted at the front of the knee joint portion 10 of said thigh member, a strong, non-elastic cord passing in front of the lower portion of

said thigh member in engagement with said roller and having its lower end secured to the rear portion of said shank member, and an elastic member secured to the upper end 15 of said cord, said elastic member being arranged to automatically bring said shank member forward into alignment with said thigh member.

In testimony whereof I hereunto affix my 20 signature.

RAY TRAUTMAN.
